CLAIM

The ornamental design for an electrical connector housing, as shown and described.

DESCRIPTION

FIG. 1 is a top plan view of an electrical connector housing showing our new design;
FIG. 2 is a front elevational view thereof;
FIG. 3 is a bottom plan view thereof;
FIG. 4 is a right side elevational view thereof, the left side elevational view thereof being a mirror image;
FIG. 5 is a rear elevational view thereof;
FIG. 6 is a cross-sectional view thereof taken along line 6—6 of FIG. 2;
FIG. 7 is a cross-sectional view thereof taken along line 7—7 of FIG. 2;
FIG. 8 is a front and upper right perspective view thereof. The broken line showing of the conductors, corresponding housing and other related members is included for the purpose of illustrating environmental elements only and forms no part of the claimed design.
